UNITED STATES PATENT OFFICE.

JOSEPH B. STRAUSS, OF CHICAGO, ILLINOIS.

ELECTRIC RAILWAY.

Application filed July 31, 1915, Serial No. 42,961. Renewed October 14, 1920. Serial No. 417,016.

To all whom it may concern:

Be it known that I, JOSEPH B. STRAUSS, a citizen of the United States, residing at Chicago, in the county of Cook and State 5 of Illinois, have invented a certain new and useful Improvement in Electric Railways, of which the following is a specification.

This invention relates to surface contact electric railway systems—that is to say, systems in which a series of exposed contacts are located along the trackway to be successively engaged by contact devices carried by the car. My invention has for its object to improve such a system and to render it 10 free from danger by reason of exposed live contacts. According to my invention the contacts are normally disconnected from the supply circuit and are successively brought into engagement therewith only for the 15 short spaces of time occupied by the passage of the car and while current is being taken from them for propulsion of the passing car. According to my invention two separate circuits are employed, one that 20 supplies electric current for running the car and another to actuate what I term the "exciters"—that is to say, electrical devices that successively connect the surface contacts along the trackway with the supply 25 circuit at the moments current is to be taken therefrom, and only at such times. The invention relates to improvements in such a 30 system as I have referred to, as will be herein pointed out.

The invention is illustrated in the accompanying drawings, wherein—

Figure 1 is a plan view of a double track electric railway system embodying my invention;

Figure 2 is a sectional view taken on line 40 2—2 of Fig. 1, showing a portion of the car on one of the tracks;

Figure 3 is a view showing a side elevation of one of the cars in position on the 45 track;

Figure 4 is a diagrammatic view showing the electric circuits on the car;

Figure 5 is a diagrammatic view showing the electric circuits associated with the 50 track;

Figure 6 is a plan view of one form of rectifier;

Figure 7 is a sectional view taken on line 55 7—7 of Fig. 6;

Figure 8 is a plan sectional view taken on line 8—8 of Fig. 3;

Figure 9 is a sectional view taken on line 9—9 of Fig. 8;

Figure 10 is a diagrammatic view showing a modification of the circuits on the car 60 for a direct current;

Figure 11 is a diagrammatic view showing the circuits associated with the track when a direct current is used;

Figure 12 is a diagrammatic view showing the arrangement of the shifting bars associated with the contact devices on the car 65 when the car is going around a curve;

Figure 13 is a sectional view taken on line 13—13 of Fig. 8;

Figure 14 is a sectional view taken on line 14—14 of Fig. 8;

Figure 15 is a diagrammatic view showing an arrangement of electric circuits on the car, where the exciter switch can be left 75 open after the car is started.

Like numerals refer to like parts throughout the several figures.

Referring now to the drawings, I have shown an electric railway system involving 80 a double track, one track having the usual rails 1 and the other having the usual rails 2.

Located between the rails of each track and suitably spaced apart are a series of feed contacts 3 and a second series of exciter contacts 4. Running along the side of the track, and preferably between the two tracks when a double track is used, are the main feeder cables 5 and 6 contained in 85 suitable insulating conduits 7. Located at intervals along the track and preferably opposite the feed and exciter contacts are a series of tube boxes 8, these boxes being 90 preferably water-proof iron boxes placed in the ground at one side of the track or between the two tracks. Contained within each tube box is a rectifier tube 9.

When there is one track there is a single rectifier tube in each box, and when there are two tracks, as shown in Figs. 1 and 95 2, there are two of these rectifier tubes in each box.

Each of these rectifier tubes, one form of which is shown in Figs. 6 and 7, consists of a vessel having the air exhausted, the vessel being preferably of 100 metal and lined with some insulating material 10, such as glass, enamel, quartz, porcelain or the like, it being understood that

this insulating material must be some substance that will not absorb moisture and which is non-combustible. There is a layer 105 of this insulating material on the inside of 110

the rectifier tube. Contained within each rectifier tube is a quantity of mercury 11. Projecting into each tube are three electrodes 12, 13 and 14. These electrodes are 5 made of any suitable material, such as graphite, and are properly insulated from the tube by the insulating bushings 15, the electrodes 12, 13 and 14 being the anodes. Each tube is also provided with two cathode 10 electrodes 16 and 17 which are placed below the surface of the mercury. There is also a starting anode electrode 18. The rectifier tubes are preferably provided with an air connection 19 provided with a valve 20 so 15 that the air can be easily exhausted therefrom.

Referring now to Fig. 5, which shows a diagram of circuits associated with the rectifier tubes, the electrode 12 of each rectifier tube is connected by a conductor 21 with a conductor 22 leading to the main feeder cable 5. The conductor 21 is also connected by conductor 23 with one of the rails 2. It will be noted that by means of the conductors 22 and 23 the feed conductor 5 is grounded to the rail 2. The electrode 13 is connected by a conductor 24 with the feeder cable 6. The electrode 17 is also connected with conductor 24 by conductor 25. The electrode 14 is connected by conductor 26 with the conductor 27, which leads to the exciter contact 4, said conductor 27 also leading to the exciter resistance 28, said exciter resistance being connected by conductor 29 with electrode 18. The electrode 16 is connected by conductor 30 with the feed contact 3. It will be understood that each of the rectifier tubes is connected in the same way, the similar parts in each one being given the same reference characters. The mercury rectifier tubes are mounted upon slate panels 31, the slate panels and mercury tube rectifiers being enclosed in the tube boxes 8. The main feeder conductors 5 and 40 6 run back to the source of electric supply, which in the present instance is shown as an alternating current generator 5^a, the circuit of which contains the coil 5^b of a transformer. The coil 5^c of said transformer is 45 connected with the feeder conductors 5 and 6. It will be noted that the feeder conductor 5 is grounded through the rail 2 at each rectifier tube.

Referring now to the circuits on the car 55 illustrated in Fig. 4, each car is provided with two contact devices which move along with the car. These contact devices are preferably in the shape of bars, one of them the feed bar 32 engaging the feed contacts 3 and the other the exciter bar 33 engaging the exciter contacts 4, the bars being of such 60 length that as the car moves along they engage the forward feeder and exciter contacts before leaving the rear contacts. A conductor 34 leads from the feed bar 32 to

the motor 35, which is a direct current motor, there being in the connection a circuit breaker 36 and any suitable motor controller 37 operated by handle 80. A conductor 38 leads from the other terminal of the motor 70 and connects with the main re-actance coils 39 and 40. A conductor 41 connects the coil 39 through the wheel 42 with the rail 2, thereby grounding said conductor. A conductor 43 connects the coil 40 with the 75 exciter bar 33. The lamps 44 on the car are connected in a circuit between the conductors 34 and 38. There is also located on the car an exciter battery 45, which is connected by a conductor 46 with conductor 43, and by a conductor 47 with feed bar 32. This circuit is controlled by the exciter switch 48. When it is desired to use a direct current instead of an alternating current, the circuit arrangement shown in Figs. 10 and 11 may be used. In this arrangement the main feed wire 50 (see Fig. 11) is provided with a direct current in any desired manner, as by generator 50^a having a grounded terminal 50^b, and is connected by a conductor 51 with an electrode 52 associated with the mercury tube 53. This mercury tube is also provided with an electrode 54, which is connected by a conductor 55 with the exciter contact 4. The mercury tube 53 is also provided with an electrode 56 which is connected by a conductor 57 with the feed contact 3. This mercury tube is provided with a fourth electrode 58, which is connected by a conductor 59 with the ground through a spark gap 60. One of the rails of the track is grounded, as shown at 61.

Referring now to Fig. 10, which shows the circuits on the car, there is provided on the car a source of electric supply such as the storage battery 62. This storage battery is connected in circuit with the primary coil 63 of a suitable induction coil. The circuit is controlled by the exciter switch 62^a. This circuit is provided with a suitable circuit breaking device, such for example, as the spring arm 64 engaging the contact 65 and adapted to be moved away from said contact by the core 66 of the induction coil when the current passes through coil 63. The breaking of the circuit stops the current and the part 64 then moves back into contact with the part 65, and the circuit is again completed, thus causing a rapid make and break of the circuit. A secondary coil 67 is associated with the primary coil 63 and as the current is made and broken, an induced current of high potential is set up in the coil 67. One terminal of the coil 67 is connected by conductors 68 and 69 with the feed bar 32. This circuit preferably contains the lamps 70. The other terminal of the coil 67 is connected by conductor 71 with the switch 130

arm 72 on the motor controller 37. Said arm 72 is preferably on the under side of the controller. This arm co-operates with contacts 74, 75, 76 and 77. When the arm 72 is on the contact 74 the circuit is open, and when it is on contacts 75 and 77, the connection is made to the front end 33^a of the exciter bar 33 through the conductor 78. When the contact arm is on the contact 76 a connection is made to the central part of the exciter bar 33 by conductor 79. The front end 33^a of the exciter bar is insulated from the main portion thereof, so that the current from the secondary 67 of the induction coil is only momentarily inserted, that is, is only in circuit for a short length of time, the length of time the part 33^a is in contact with the exciter contact 4. When the car is running, the arm 72 is either on contact 75 or 77. At the other end of the bar 33 is a section 33^b, also insulated from the central portion 33, to be used when the car is running in the opposite direction. This section is connected with the other motor and controller at the other end of the car, it being understood that the car has two motors and controllers, one at each end when the car is to be run in either direction along the track. If now the car should stop with the main portion 33 of the exciter bar in contact with the exciter contact 4, the device could not be started up by having the lever 72 engage contact 75 or 77. If, however, the lever is moved to engage contact 76, then the circuit is completed through the central part of the contact bar 33 and the car can be started. The source of electric supply 62 on the car need only be used in first starting the car, as current after the car is moving can be taken from the main source of current supply. Under these conditions the exciter switch 62^a is moved out of contact with contact 62^b, and in contact with contact 62^c connected with conductor 62^d, grounded at 62^e, and the switch 65^a is moved to disconnect it from the contact 65^b and connect it with contact 65^c and conductor 65^d. The contact arm 72 is connected with the handle 80 of the controller so as to move therewith. The motor 81 on the car is connected with the controller 37 and by conductor 82 with conductor 69. An overload circuit breaker 82^a is placed in circuit with the motor. Said motor is connected through the field coils 83 and conductor 84 with the wheel 42, and thence with the rail 2 and the ground. In view of the length of the feeder bar and exciter bar, some means is provided for insuring their contact with the contacts along the roadway as the car is passing around curves. As herein shown, each bar is provided at the center with a take-up joint arranged so as to permit the bars to lengthen and shorten as the car passes around curves. This con-

struction is shown in Figs. 3, 8 and 13. In the construction shown, these bars are made up of three sections, a central section and two end sections. The central section 90 of each bar is connected to a laterally sliding supporting piece 91 connected with the car body, the connection between the piece 90 and the supporting piece 91 being made by the slotted links 92. The opposite ends of the piece 90 are beveled and they overlap beveled ends on the other sections of the bar, there being preferably a dove-tailed projection 93 on one part which engages a dove-tailed opening on the other so as to permit the parts to slide along one another but prevent their becoming disengaged. The coil springs 94 are located between the parts 91 and the bars which tend normally to press them downward against the contacts 3 and 4 but leaves them free to move up and down as varying conditions along the roadway require, the slots in the links 92 permitting this up and down movement. The supporting pieces 91 are connected with the sliding cross-piece 95 which is slidably connected with the car body. In the construction shown, this cross-piece is connected by a rod or bolt 96 with a support 97 attached to the car body. The cross-piece 95 is provided with a slot 98 through which the bolt 96 passes so that the cross-piece is free to slide back and forth. The support 97 is connected by means of brackets 99 with the body of the car. It will thus be seen that there is a laterally movable supporting piece for these bars, by means of which they are connected with the car body. The exciter bar and feed bar are connected at each end of the car with a shifting lever 100. The connection to the shifting levers is made by means of the slotted links 101 which connect the bars with the support or hanger 102, said support or hanger being connected to the shifting lever at separated points by the pivots 103. The shifting lever is pivotally connected between its ends to the car truck 104, this connection being made by the pivot 105. The car truck is provided with a slot 104^a through which the shifting lever passes (see Fig. 14), this slot being of sufficient size to permit the proper movement of this shifting lever. It will be noted that the pivotal connection between the shifting lever and the truck, made by the pivot 105, is at a distance from the main pivot 112, which connects the truck with the body, thereby insuring the proper movement of the shifting lever as the car moves around curves. The shifting lever 100 is pivotally connected at one end to the car body by means of the pivot 106, which is connected with a bracket 111 attached to the car body. It will thus be seen that this connection permits the bars to move with relation to the body as the trucks pass

around curves. There are two trucks, one at each end of the car, as is usual in such cases. The laterally movable support 95 is connected at each side with the trucks by 5 the pivoted links 107, said links being pivoted at one end to the laterally movable support by the pivots 108 and at the other end to the truck by the pivots 109. It will be seen that by means of this arrangement the 10 bars automatically adjust themselves when going around curves, and are kept in contact with the contacts 3 and 4.

I have shown diagrammatically in Fig. 12 the position of the parts when the car is 15 going around a curve. The contacts 3 and 4 may be placed closely together at the curves and should be located so as to make proper contact with the bars.

In Fig. 15 I have shown an arrangement 20 of circuits for an alternating current where the exciter switch need only be closed to start the car the first time and can then remain open. In this construction a conductor 34^a is connected with the contact 34^b of the switch 37^a and is also connected with exciter bar 33, there being a resistance 34^c in said circuit. With this construction the exciter circuit passes around the motor instead of through it.

30 I have described in detail a particular construction embodying my invention, but it is of course evident that the parts may be varied in many particulars without departing from the spirit of the invention, and I therefore do not limit myself to the particular construction shown.

The use and operation of my invention are as follows:

If the car is at rest on the track the feed 40 bar and exciter bar will be in contact with the feed contact and exciter contact. In order to start the car the motorman closes the exciter switch 48 on the car (see Fig. 4). This connects the exciter battery 45 in circuit, the circuit being traced as follows: From the battery 45 through conductors 46 and 43 to exciter bar 33, thence through exciter contact 4, thence by conductor 27 to exciter resistance 28, thence by conductor 29 45 to electrode 18, thence to electrode 16 and through conductor 30 to feed contact 3, thence to feed bar 32 and thence by conductor 47 back to the battery. There is a small bridge of mercury between the electrodes 16 and 18 and this mercury is evaporated by 50 the current from the battery following which an arc results which jumps to one or the other of the main anode electrodes 12 or 13, and alternates between these electrodes 55 during the regular operation, thus automatically connecting up the circuit with the feed conductors 5 and 6. The motorman proceeds to operate the motor by the controller 37. The circuits are then traced as follows. 60 The current in the feed conductors being an

alternating current, the circuit will be traced at the instant it is positive in the main conductor 6 (see Fig. 5). At this instant the electrode 13 is then positive and the arc is free to flow between the electrode 13 and the 70 electrode 16, the current then passing from the feeder conductor 6 through conductor 24 to electrode 13, thence to electrode 16, thence through conductor 30 to feed contact 3, thence through feed bar 32 to conductor 34, thence through motor 35 and conductor 38, thence through the main reactance coil 39, thereby charging it, and while the value of the alternating current 75 wave is decreasing, reversing and increasing the reactance coil discharges, thus maintaining the arc until the voltage reaches the value required to maintain the current against the counter electromotive force of the load and reducing the fluctuations in the direct current. The current flows from the reactance coil 39 through conductor 41 to the wheel 42, and thence to rail 2, and thence by conductors 23 to 22 to feed conductor 5. At the end of the first half of 80 the cycle of the alternating current in the feed conductor when the voltage drops to zero, the inductance of the main reactance coil 39 maintains the current and a local circuit is formed through electrodes 12 and 16 85 and reactance coil 39 which maintains the arc until the voltage in feeder conductor 5 has risen to a value which will maintain the arc.

This local circuit is as follows: From main reactance coil 39 through conductor 41 to wheel 42, thence to rail 2, thence by conductors 23 and 21 to electrode 12, thence to electrode 16, thence by conductor 30 to feed contact 3, thence to feed bar 32 and thence by conductors 34 and 38 to main reactance coil 39.

In the next half cycle of the alternating current the feeder conductor 5 at the point where conductor 22 connects therewith, becomes positive, the electrode 12 is then positive and the arc is free to flow between the electrodes 12 and 16. The circuit is then traced as follows: From feed conductor 5 through conductors 22 and 21, to electrode 12, thence to electrode 16, thence through conductor 30 to feed contact 3, thence to feed bar 32, thence through conductor 34 to motor 35, thence through conductor 38 to main reactance coil 40, thence through conductor 43 to exciter bar 33, thence to exciter contact 4, and thence by conductor 26 to electrode 14 and thence to electrode 17 and thence by conductor 24 to feeder conductor 6. The local circuit due to the reactance coil as above described is then through contact 4 through electrodes 14, 17 and 13, reactance coil 40, said circuit being traced as follows: From reactance coil 40 through conductor 43 to exciter bar 33, thence to exciter con- 125

tact 4, thence through conductor 26 to electrode 14, thence to electrode 17, thence through conductors 25 and 24 to electrode 13, thence to electrode 16, conductor 30 to 5 feed contact 3, and thence through feeder bar 32 and thence through conductors 34 and 38 to reactance coil 40. This local circuit maintains the arc until the voltage in feed conductor 6 at the point where conductor 24 10 connects therewith, rises to a value which will maintain the arc. After the first tube is started in operation by the exciter battery, the exciter switch 48 may be opened and does not need to be again closed until 15 the current through the motor on the car is cut off or fails for some reason. After the starting of the first rectifier tube and while the current is passing through the motor it will be seen that the feed bar 32 and the 20 exciter bar 33 are alive and when they reach the next contacts ahead, being still in engagement with the adjacent contacts at the rear, current is taken from said bars to start the rectifier tube associated with the contacts ahead. The starting or exciter circuit in that case will then be traced as follows: From exciter bar 33 to contact 4, thence by conductor 27 to resistance 28, thence by conductor 29 to electrode 18, thence to electrode 16, thence by conductor 30 to feed 25 contact 3, thence to feed bar 32, thence by conductors 34 and 38 to coil 40 and thence by conductor 43 to exciter bar 33. The feed bars and exciter bars on 30 the car are longer than the distance along the track between the adjacent contacts, so that they will be in contact with the rear contacts a sufficient length of time to permit the rectifier at the forward contact to be 35 properly started. When the motor is stopped and it is again desired to start up the car, the exciter switch is again closed. If desired, the circuits may be arranged so that the exciter switch need only be closed 40 to start the car the first time and can then remain open even when the motor is stopped. The circuits in this construction are shown 45 in Fig. 15, wherein there is a conductor 34^a connected with a contact 34^b associated with the switch 37^a, and also connected with the exciter bar 33, there being a resistance 34^c in said circuit. When the switch 37^a is moved to break the circuit through the motor it engages contact 34 and completes the 50 circuit through the conductor 34^a and resistance 34^c, and the exciter circuit is then transferred and instead of passing through the motor, passes through resistance 34^c and conductor 34^a back to the exciter bar, the 55 circuit being otherwise as above set out. It will be seen that by means of this construction the alternating current is changed to a direct current and passed through a direct current motor on the car, and that connection is made between the motor and the 60

source of electric supply without the aid of moving switches or contacts except those on the car which engage the feeder and exciter contacts 3 and 4. As the car moves along the contact bars thereon successively contact with the contacts between the rails and the circuit is successively established through the rectifier tubes along the track. When the contact bars pass from the feeder and exciter contacts the 70 mercury arc in the tube associated with said contacts is extinguished as the voltage in the current becomes zero, thus disconnecting the main feed conductors from the feed contacts and leaving these contacts at the rear 75 of the car dead and harmless.

In this system the feed conductors are completely concealed and protected and there are only a series of exposed contact points on the street or right of way, which 80 contacts are dead and harmless except at the instant when the car is passing over them, and yet there is a continuous current into the car from the alternating current feed conductors. It will further be seen that the 85 connections and disconnection between these contacts and the source of electric supply is made without moving switches and the like, the current itself acting to make the connection through the mercury vapor, the connection instantly being cut off when the feed bar moves off the contact. It will further be seen that this construction provides a 90 cheap and efficient construction requiring very little care or expense for maintenance under constant and heavy service, and that a perfectly safe construction is provided. This device is particularly adapted for the 95 use of alternating currents, but my invention may also be used in connection with direct currents.

I have shown in Figs. 10 and 11 the circuits when a direct current is used. In this construction when it is desired to start the car the motorman closes the exciter switch 110 62^a so as to complete the circuit through the source of electric supply 62 and the coil 63 as shown in Fig. 10. The current then passes through the coil 63, energizing the core 66 and causing it to attract the spring 64, thereby breaking the circuit. The current then ceases and the spring 64 moves back and completes the circuit, this operation being repeated while the switch 62^a is closed. At each make and break of the circuit a current of high potential is induced 115 in the coil 67. This current then passes through conductor 71 and when the controller handle 80 is moved to start the motor, the switch 72 is also moved. If the car is stopped so that the central part 33 engages the exciter contact 4, the switch 72 is moved to contact 76 and the current then passes through conductor 79 to exciter bar 33 and thence to exciter contact 4. If the car is 120 125 130

so that the part 33^a is in contact with the exciter contact 4, or if the car is moving along, the switch 72 will be moved into contact with contacts 75 or 77 and the current 5 passes through conductor 78 to the end 33^a of the exciter bar and thence to the exciter contact 4. The current then passes from exciter contact 4 through conductor 55 to electrode 54, thence through the mercury tube 10 to electrode 58, thence through spark gap 60 to the ground, thence through grounded conductor 61 to rail 2, thence to wheel 42, conductor 84, and to conductors 69 and 68, back to coil 67. The passage of this current 15 through the tube 53 from electrode 54 to electrode 58 breaks the mercury bridge, causing an arc to form. This produces mercury vapor in the tube and the arc immediately jumps between electrodes 52 and 56, 20 thus connecting the motor 81 with the main circuit. This circuit is then traced as follows: From the generator 50^a to the main feed wire 50 (see Fig. 11), thence by conductor 51 to electrode 52, thence to electrode 56 and thence by conductor 57 to feed contact 3, thence to feed contact bar 32, thence by conductor 69 through circuit breaker 82^a 25 to conductor 82, controller 87 and motor 81, thence by conductor 84 to wheel 42 and rail 2, thence to the ground and thence back to the generator 50^a through the grounded terminal 50^b. When the car is moving along, the exciting current can be taken from the main source of current supply by moving 30 the switch 65^a into contact with contact 65^c and the switch 62^a into contact with contact 62^c. The current from the main line conductor 50 is now passing through the feed bar 32 and the motor, and the thing to be 35 accomplished is to start up the mercury tube 53 just ahead of the car as soon as the part 33^a strikes the next exciter contact 4. As soon as this is done, that is, as soon as the section 33^a strikes the exciter contact 4 40 ahead, the portion of the current then flowing through the generator 50^a, conductors 50 and 51 and mercury tube 53 now in operation, and contact 57 and feeder bar 32 passes from said feeder bar 32 through conductors 69 and 65^a to switch 65^a, thence 45 through coil 63; thence through switch 62^a and conductor 66^a to ground 62^c and thence back to the generator. A current is then induced in the coil 67 and passes through the 50 mercury tube 53 ahead of the car so as to start it, said circuit being traced as hereinbefore described, it being understood that before the contact bars leave the contacts of any given mercury tube through which current is passing to the motor, a part of that current may be directed through the induction coil so as to start the mercury tube ahead in operation, and then the current 55 from the motor is taken through this mer-

cury tube, because the contact bar 32 engages the feeder contact 3 connected with said mercury tube ahead before it leaves the feeder contact 3 connected with the mercury tube at the rear. When the contact bar leaves the contact 3 connected with the mercury tube at the rear, the current through said mercury tube stops and the contact 4 which the bar 32 has just left instantly becomes dead and inert, and this is done without any movable switches or parts between the contact bar 32 and the main feeder conductor 50. 65 70 75

I claim:

1. An electric railway system comprising a track, a series of separated feed contacts 80 extending along said track, a series of separated exciter contacts also extending along said track, two feed wires extending along said track and carrying an alternating current, a rectifier associated with each feed and exciter contact and electrically connected with said feed wires and said contacts and adapted to rectify the alternating current and produce a direct current, contact bars on the car adapted to successively engage said contacts as the car moves along the track, said contact bars adapted to engage the forward contact before leaving the rear contact, and means adapted to be successively brought into circuit with said exciter contacts for successively starting the operation of said rectifiers, a motor on the car adapted to be successively connected with said feed contacts. 90 95

2. An electric railway system comprising 100 a track, a series of separated feed contacts extending along said track, a series of separated exciter contacts also extending along said track, feed wires extending along said track, a series of mercury rectifiers at intervals along said track, one for each feed contact, said rectifiers electrically connected with said feed wires, each rectifier electrically connected with one feed contact and one exciter contact. 105 110

3. An electric railway system comprising a track, a series of separated contacts extending along said track, alternating current feed wires extending along said track, a series of rectifiers extending along said track and connected with said feed wires, each rectifier connected with one of said contacts, a car, a motor on the car, means on the car for connecting said motor with said contact and rectifier, said rectifier adapted to rectify said alternating current so as to produce a direct current through the motor on the car. 115 120

4. An electric railway system comprising a track, a series of separated contacts extending along said tracks, a car adapted to move along said track, a direct current motor on said car, means on the car for successively connecting said motor with said contacts as 125

the car moves along the track, alternating current feed wires extending along said track, and means associated with each of said contacts for successively rectifying a portion of said alternating current as the car passes along said contacts so as to provide a direct current for the motor on the car.

5. An electric railway system comprising a track, a series of separated contacts extending along said tracks, a car adapted to move along said track, a direct current motor on said car, means on the car for successively connecting said motor with said contacts as the car moves along the track, 10 alternating current feed wires extending along said track, means associated with each of said contacts for successively rectifying a portion of said alternating current as the car passes along said contacts so as to provide 15 a direct current for the motor on the car, and means for automatically disconnecting said contacts from said feed wires when the car leaves the contacts.

6. An electric railway system comprising a track, feed wires extending along said track and carrying an alternating current, a series of mercury rectifiers at intervals along said track, a car, a motor on said car, initial starting means for starting each rectifier in 20 operation as the car reaches it, and means associated with each rectifier for automatically connecting it in circuit with said motor and said feed wires as soon as the initial starting means is set in operation.

35 7. An electric railway system comprising a track, feed wires extending along said track and carrying an alternating current, a series of mercury rectifiers at intervals along said track, a car, a motor on said car, initial starting means for starting each rectifier in operation as the car reaches it, means associated with each rectifier for automatically connecting it in circuit with 40 said motor and said feed wires as soon as the initial starting means is set in operation, and means for maintaining the electrical connection through the rectifier while the alternating current wave is passing through the zero point.

45 8. An electric railway system comprising a track, feed wires extending along said track and carrying an alternating current, a series of mercury rectifiers at intervals along said track, a car, a motor on said car, initial starting means for starting each rectifier in operation as the car reaches it, means associated with each rectifier for automatically connecting it in circuit with 50 said motor and said feed wires as soon as the initial starting means is set in operation, means for maintaining the electrical connection through the rectifier while the alternating current wave is passing through the zero point, and means for automatically 55 breaking the circuit through the rectifier

after the motor on the car is connected with the adjacent rectifier.

9. An electric railway system comprising a track, a feed wire extending along said track, a series of exposed contacts located 70 at intervals along the track and normally disconnected from said feed wire, a car adapted to travel on said track, a motor on said car, a contact device on the car connected with said motor and adapted to successively engage said contacts as the car moves along the track, a circuit varying device associated with each contact and electrically connected therewith and with said feed wire, said circuit varying device 75 consisting of fixed parts normally electrically disconnected, and means free from a movable switch contact for electrically connecting them as the car moves along said contacts.

80 10. An electric railway system comprising a track, a feed wire extending along the track, a series of exposed contacts at intervals along said track, a car adapted to run along said track, a motor on said car, a contact device on the car connected with said motor and adapted to be successively connected with said contacts as the car moves along the track, a circuit varying device 85 associated with each contact and consisting of fixed parts only, each circuit varying device connected with its associated contact and with said feed wire, so that the circuit is normally open, and means for automatically and successively closing the circuit 90 through said circuit varying devices as the car moves along the contacts.

95 11. An electric railway system comprising a track, a feed wire extending along the track, a series of exposed contacts located 105 at intervals along the track, means for successively connecting the said contacts with the feed wire, comprising a series of mercury vapor starting means having fixed electrodes connected respectively with the contacts and with the feed wire, said terminals being normally electrically disconnected, a car movable along the track, a motor on the car, a contact device on the car adapted to 110 make engagement with said surface contacts successively as the car moves along the track, and means under the control of the operator on the car for successively exciting the said mercury vapor starting means to cause mercury vapor to be produced, thereby electrically connecting the fixed electrodes connected respectively with the feed wire and a surface contact.

115 In testimony whereof, I affix my signature in the presence of two witnesses this 125 14th day of July, 1915.

JOSEPH B. STRAUSS.
